FIG. 3.

INVENTOR

Howard A. Kehl

UNITED STATES PATENT OFFICE

154,402

DESIGN FOR A SLIP-ON BELT BILLFOLD

Howard A. Kehl, Detroit, Mich.

Application March 29, 1948, Serial No. 145,413

Term of patent 14 years

(Cl. D87—3)

To all whom it may concern:

Be it known that I, Howard A. Kehl, a citizen of the United States, residing at Detroit, in the county of Wayne and State of Michigan, have invented a new, original and ornamental Design for a Slip-On Belt Billfold, of which the following is a specification, reference being had to the accompanying drawing, forming part thereof.

I claim:

The ornamental design for a slip-on belt billfold, as shown.

HOWARD A. KEHL.
